UNITED STATES PATENT OFFICE.

STANLEY E. COLLINSON, OF NEWTON CENTER, MASSACHUSETTS.

GOLF CLUB AND METHOD OF MAKING THE SAME.

Application filed January 12, 1926. Serial No. 80,708.

This invention relates to golf clubs and particularly to clubs having a metal striking head.

Heretofore it has been customary to secure the heads of golf clubs to the shafts by providing a socket in the head in which the shaft is inserted and secured against separation and rotation by pins inserted through the shaft and head. It is difficult to make a connection in this manner between the head and shaft which will not loosen in use, and when such looseness or twisting play appears, the club is useless for the reason that the player cannot cause the ball struck therewith to pursue a definite desired course, because he can never be sure of the direct angle of contact between the head of the club and the ball.

An object of this invention is to provide an improved golf club and method of making the same, by means of which all of the advantages of a metal head may be obtained, and by means of which the head may be secured to the shaft firmly and securely in such a manner that the head and shaft cannot become separated or have relative movement of any kind, even after long use of the club.

A further object of the invention is to provide an improved club and method of making the same by means of which the shaft will always have a specific predetermined relation to the striking face of the head, even in quantity production.

A further object is to provide an improved golf club having a metal head connected to the shaft in such a manner that it will not become loose or separated during use; and which will be relatively simple, strong, durable, uniform and inexpensive.

Various other objects and advantages will be apparent from the following description of two embodiments of the invention, and the novel features will be particularly pointed out hereinafter in connection with the appended claims.

In the accompanying drawing:

Fig. 1 is an elevation partly in section of a golf club constructed in accordance with this invention;

Fig. 2 is an elevation of the shaft of the same; and

Figs. 3 and 4 are different elevations of a modified construction of a shaft which may be employed in place of that shown in Figs.

1 and 2.

Referring now to the embodiment illus-

trated in Figs. 1 and 2, a tubular shaft 1 of suitable metal, such as steel, is pinched together or flattened at one end, as at 2, so as to change its cross sectional shape in the head-end portion thereof. This shaft is preferably supported at both ends in a suitable casting form (not shown) having a cavity, for the reception of the cast metal, surrounding the shaft intermediate its ends. A suitable molten metal, such as aluminum or alloys thereof, is then supplied to the cavity which solidifies about the lower end of, and between the ends of the shaft.

When such a product is removed from the casting form, the tip end of the shaft 2 which was supported in the form and which now projects slightly from the bottom of the cast head 3 may be removed from the head in any suitable manner, such as by filing, grinding, or cutting, so that the bottom of the cast head will be smooth and continuous as shown in Fig. 1. By reason of the non-circular cross-section of the portion 2 of the shaft, the cast head 3 cannot rotate or twist upon the shaft, and by reason of the shoulder 4 formed between the pinched in or flattened section 2 of the shaft and the tubular portion thereof, which shoulder appears clearly in Fig. 2, the shaft will be firmly anchored in the stem 5 of the cast head 3, and separation of the shaft and cast head effectively prevented. The shaft will, of course, be positioned in the casting form in a particular desired angular relation to the striking face 6 of the cast head 3.

By supporting the shaft 1 at both ends in the form, and casting the head thereon between the ends of the shaft, the inrushing molten metal will not flex or displace the section of the shaft within the casting cavity of the form sufficiently to vary the angular relation between the axis of the shaft and the striking face 6 of the head. Furthermore, any softening of the shaft by reason of the heat from the molten metal will not result in a change in the angular relation of the axis of the shaft to the striking face 6, and therefore one can always obtain clubs having uniform and desired relation between the axis of the shaft and the striking face 6 of the head.

In order to avoid injury to the shaft by reason of the heat of the metal being cast thereon, which, for example, might take the life out of the shaft if the latter is made of steel, I preferably coat the portion of the

shaft to be encased in the head and stem thereof, with a suitable heat resisting preparation, such as asbestos paint, which material is shown by stippling in Fig. 2, before it is inserted into the casting form, and I have found that with this arrangement no injury to the steel shaft occurs. The head, of course, may be cast in any suitable manner, such as by sand-casting or die-casting, the anchoring of both ends of the shaft in the casting form being particularly desirable when the heads are die-cast thereon, because of the danger of flexing the encased section of the shaft by the molten metal as it rushes in under high pressure in the die-casting operation.

In Figs. 3 and 4 I have illustrated another form of the shaft. This modified shaft 7 may be formed of tubular stock, such as of tubular steel or other metal, and is pinched in at one end as at 8, in a manner similar to the pinching as at 2 in Figs. 1 and 2 and in addition is also preferably pinched in at one or more other points 9 and 10 spaced from the portion 8. In this form, however, the pinching is shown as less pronounced than in Figs. 1 and 2 although it will be understood that the pinching may be, if desired, as complete as in Figs. 1 and 2, particularly at the lower end.

The lower end of the shaft 7 may also be treated with a heat resisting material, such as asbestos paint, the same as described in connection with Figs. 1 and 2, and such a coating is also shown by stippling in Figs. 3 and 4. The additional pinched points in the shaft of the Figs. 3 and 4 provide an increase in the locking effect between the shaft and the head, so that twisting and loosening of the shaft in the head during use of the club is more effectively avoided.

In both of the illustrated embodiments of the invention, the shafts are preferably so placed in the casting forms that the pinched or flared portions 2 or 8 run crosswise of the head, for the reason that a more satisfactory and durable club, and an increase in strength in the connection between the shaft and head are obtained, owing to the usual closeness of the shaft to the end of the head. For example, as shown in Fig. 1, the metal between the pinched portion 2 and the end of the head beneath the inclined stem 5, would be so slight that the shaft might tear loose therefrom, were it not that increased metal therefor is provided by the positioning of the flare crosswise of the head.

It will also be observed that in accordance with this invention, the shaft may always be positioned in a definite desired and uniform angular relation to the striking face of the head, and that because of the casting operation the clubs may be manufactured rapidly in quantities at a relatively low cost. A

club constructed in this manner will be 65 strong and durable, inexpensive and have a connection between the shaft and head which will not become loose or broken in use, and which will not require an increase in the usual size of the clubs of any particular 70 character. By reason of the treatment of the shafts before insertion into the casting form, and by reason of their support at both ends, and the casting of the metal thereon at a point between its supported ends, the product will run uniform, that is, the striking face will always have the same angular relation to the axis of the shaft.

It will be obvious that various changes in the details, which have been herein described 80 and illustrated for the purpose of explaining the nature of the invention, may be made by those skilled in the art within the principle and scope of the invention as expressed 85 in the appended claims.

I claim:

1. The method of making a golf club which includes coating the head end of a metal handle shaft with an asbestos paint, and casting a metal head upon said treated 90 end, whereby the handle shaft will be substantially unaffected by the heat from the casting operation.

2. The method of making a golf club which includes supporting a handle shaft at 95 its ends in a casting form, casting a metal head upon said shaft intermediate of its ends, and then cutting off the bottom projecting end of the shaft.

3. The method of making a golf club 100 which includes pinching a portion of the head end of a tubular handle shaft to provide head end sections of relatively different shapes, and casting a metal head upon said sections, whereby the head and shaft 105 will be firmly united against relative twisting and separation.

4. A golf club comprising a tubular handle shaft having a head cast upon one end thereof, said shaft having portions of the 110 section within the head pinched in to provide a non-circular section connected with the remainder of the encased portion by a shoulder, whereby the head will be firmly held against both rotation on and separation from 115 said shaft.

5. A golf club comprising a tubular metal shaft having a portion adjacent one end flattened somewhat, and a head cast upon said shaft at the flattened end section and 120 encasing said section beyond the limits of said flattened portion, with the plane of the flattened section extending crossways of the head.

In witness whereof, I hereunto subscribe 125 my signature.

STANLEY E. COLLINSON.
